UNITED STATES PATENT OFFICE.

JOSIAH S. ANDREWS, OF CLOQUET, MINNESOTA.

FOLDING CRATE.

SPECIFICATION forming part of Letters Patent No. 600,822, dated March 15, 1898.

Application filed June 12, 1897. Serial No. 640,414. (No model.)

To all whom it may concern:

Be it known that I, JOSIAH S. ANDREWS, of Cloquet, in the county of Carlton and State of Minnesota, have invented certain new and

5 useful Improvements in Folding Crates; and I do hereby declare the following to be a full, clear, and exact description of the invention, such as will enable others skilled in the art to which it appertains to make and use the same.

10 The invention relates to a folding crate or case more especially designed for use as a case for packing eggs, but embodying a construction applicable to other uses.

15 It relates to the manner of hinging the sides or front and rear boards of the crate and the end boards thereof to the base-plate, whereby they are adapted to be folded into compact shape for transportation or to be opened up for use, the object being to obtain a simple, 20 inexpensive, and substantial crate which can be folded into compact shape for transportation when not in use and which is adapted to thoroughly protect the contents of the case when opened up for that purpose.

25 The construction by which the foregoing objects are attained will be understood from the following description, with reference to the drawings, in which—

30 Figure 1 represents a front perspective view of a case embracing the invention, with the front side board turned down out of the way to show the arrangement of the other parts. Fig. 2 represents a longitudinal section through the case. Fig. 3 shows one of the side boards 35 in end elevation; and Fig. 4, an inner face view of one of the end boards, with its hinged extension in the open position.

1 represents the bottom board of the case, made, preferably, in the rectangular form indicated and with a length about double that of the width. The front and rear edges of this plate are provided with narrow upright strips 2, to the ends of which are secured uprights 3, said uprights forming a shallow tray in which the contents or folding pulp partition-boards for egg-carriers can be placed when not in use.

40 The end uprights 3 extend above the side uprights 2 and are provided with angle irons 5 or plates 6, having inturned flanges 7, provided with vertical slots 8, with which headed pins on the ends of the side boards 5 engage

for hinging said side boards to the end boards and allowing them to receive a vertical adjustment relative to said end boards.

55

The angle-irons 6 are secured to the edges of the end uprights 3 by screws or other suitable fastenings, and the inturned flanges 7 thereof are also secured to the inner face of the end uprights 3, as indicated. One of these angle-irons is secured to each end of each end upright, and the ends of the side boards 5 are provided each with a headed pin engaging the slot 8 is said angle-irons. The angle-irons 6 are provided near their upper 65 ends with headed pins 10, upon which are pivoted strap-irons 9, secured at their upper ends to hinged end extensions 4 4. The upper horizontal edges of the parts 3 are preferably rounded to permit the folding movement of the extensions 4, and the lower edges of the parts 4 may be correspondingly concaved for the same purpose, providing a snug folding joint between the uprights 3 and the hinged extension 4 thereof.

75

The hinged extensions 4 are provided adjacent to each edge near their upper ends with plates 11, having headed pins 12 formed thereon, and upon the edges of the side boards 5 are secured plates 13 near the upper ends 80 of said boards. These plates 13 are provided with upright slots 14, opening inward at their lower ends and adapted to engage the headed pins 12. Near the lower edges of the side boards 5 are headed pins 15, adapted to engage the slots in the plates 7 to be adjusted up and down therein. When the side plates are raised to the limit of the play of the headed pins, the open end of the slots 14 will be in position to receive the headed pins 12, 90

which at said open end inclines inward toward the vertical portion of the slot, adapting the side board to be pressed downward to engage the upper closed end of said slot 14. By this arrangement of the headed pins and open slot, which is somewhat in the nature of a bayonet-joint, the side boards 5 can be raised for engagement with the headed pins 12 and then forced snugly down in place upon the bottom strips or uprights 2, in which position they serve to firmly lock both the side boards and the end boards firmly in position. In emptying the crate the operation can be reversed by simply raising and releasing the

95

100

side and end boards, when the side boards can be folded in upon each other and over the contents of the tray and the partition-boards placed in said tray, and the end boards 5 can then be folded down upon the side boards, bringing the whole case into compact shape for transportation. The end uprights are provided on their outer faces with cleats 18 10, one at or near the bottom of the crate and one near the upper end of the hinged extension of the end board. These are secured in place by any suitable fastening, to which are added bracing staples or wires 19, extending over the cleats and passing through the 15 end boards and firmly riveted therein. The cleats are shown grooved vertically adjacent to said staples 19 at points indicated at 20 for the purpose of adapting the retaining-wires of the cover to engage with the cleats 20 to prevent lateral movement of the same. 21 indicates a removable transverse partition adapted to engage grooves 22 in the side boards 5 and also to be engaged when in place by means of parallel cleats 23 23 on the lower 25 face of the parallel cover, which serve to lock said partition 21 in place and prevent any lateral movement thereof when the case is in use for the transportation of eggs or other substance. 30 The cover 26 is provided at its ends with pendent end strips 27, which overhang the end boards 4, and with suitable fastenings adapted to engage the cleats on said end boards in either the extended or folded posi-

tion of the crate. The particular form of fas- 35 tening shown is made the subject-matter of another application, and need not, therefore, be herein particularly described.

By the construction described the case is adapted when not in use to be folded in a 40 very narrow compass compared with its open or expanded form.

The plates forming the hinged connections and fastenings of the several parts referred to are made of strap or hoop iron and are in- 45 expensive in construction and not liable to get out of order.

Having thus described my invention, what I claim as new, and desire to secure by Letters Patent, is—

The combination in a folding crate provided on its bottom board with a fixed shallow tray, rigid end uprights having hinged extensions, pivoted side boards hinged in slotted angle-irons on the end uprights, said side boards 55 being provided on their ends with plates having slots open at their lower ends, and headed pins on the inner faces of the end boards for engaging said slotted plates, all substantially as and for the purpose described.

In testimony whereof I have signed this specification in the presence of two subscribing witnesses.

JOSIAH S. ANDREWS.
